UNITED STATES PATENT OFFICE.

JAMES FRANCIS BARTLETT, OF CHICAGO, ILLINOIS.

CASH AND PACKAGE CARRIER.

SPECIFICATION forming part of Letters Patent No. 402,128, dated April 30, 1889.

Application filed September 14, 1888. Serial No. 285,369. (No model.)

To all whom it may concern:

Be it known that I, JAMES FRANCIS BARTLETT, of Chicago, in the State of Illinois, have invented certain new and useful Improvements in Cash and Package Carriers for Stores, of which the following is a specification.

The invention relates to improvements in carriers for stores, designed to carry cash and packages from the sales-counter to the cashier's desk and back; and the object of my improvements is to simplify the construction and operation of such carriers. I have attained this object in the carrier constructed as illustrated in the accompanying drawings, in which—

Figure 1 is a side view of the entire apparatus. Fig. 2 is a fragment of a side view showing a slight modification. Fig. 3 is an enlarged horizontal section on line 3 3 of Fig. 1, showing portions of the apparatus in plan view. Fig. 4 is a like view to that shown in Fig. 1, but showing the working parts in a different position. Fig. 5 is a fragment of an enlarged vertical longitudinal section. Fig. 6 is a horizontal section of the standard and the adjustable projection thereon on line 6 6 of Fig. 5. Fig. 7 is a transverse vertical section of the apparatus on line 7 7 of Fig. 6, looking toward the right. The invention consists in the parts and combinations herein-after described, and pointed out in the claim.

A designates an upright piece or standard, which is designed to be supported on the sales-counter at A' or from the store-ceiling, or both, being attached to the counter and extended up to and attached to the ceiling to give it lateral support, or attached to the ceiling and extended down over the counter and nearly to it, and supported laterally by guys connected near the bottom and extended obliquely to the ceiling. This piece is made T-shaped in cross-section in order to give it the necessary strength and at the same time make it as light as possible, there being a projection, a, at the front edge to serve as a track or way.

There is a hook, B, secured to the cashier's desk or the railing thereof, or other support, within easy reach of the cashier when at the desk.

A wire, C, is stretched between the sales-counter and the cashier's desk, at each end of which there is a frame, C', provided with a coil-spring, c, one end of which rests against the end cross-piece, c', at one end of said frame, the other end being provided with a plate or piece, c², which is grooved at each end and adapted to slide between the side bars of said frame. The wire C passes through a hole in the end cross-piece, c', and through on the inside of said spring to the piece c², to which it is secured.

The frame C', adjacent to the upright A, is pivoted to a piece, D, which has rollers d, adapted to run on the track a. Said piece D is connected in a cord-belt, D', which passes over rollers d', supported by brackets fastened to the ceiling and counter, or other stationary body, so arranged relatively to said upright as to support the belt parallel with the track a, and with the rollers d resting against the same. The tension of said belt holds the sliding piece D in whatever position it may be left on the track a without the use of catches of any kind, and at the same time leaves it free to be moved up or down thereon by a gentle pull on one side or the other of said belt.

The frame C, adjacent to the cashier's desk, is provided with a downwardly-projecting piece, c³, which engages with a bracket, B', or other stationary body under the wire C, for the purpose of keeping said frame from turning on the wire. A screw-swivel, B², is used in connection with the hook B, and a link, b, for connecting said frame, for the purpose of adjusting the tension of the wire C. By means of the springs c said wire is maintained at the proper tension, while the end adjacent to the upright A is being raised and lowered through a considerable space, said springs yielding to compensate for the varying distance between the extreme points of connection caused by shifting the point of connection with said upright.

A car or carriage, E, is provided, having wheels or rollers e, adapted to run on the wire C, and pendent hooks e' for connecting the parcel-basket E'. Said car is provided with guards e² over its wheels, which are curved down in front of the wheels nearly to

their center, horizontally; and each of the frames C is provided with a tilting latch, F, which is pivoted to an upwardly-projecting part of said frames, respectively, at f. Under the rear end is a spring, f', which maintains the opposite end, f'', extended over the wire C in proper position to strike the inclined part of said guards curved down in front of said wheels. The end f'' of said latches is bifurcated and provided with a roller, f³, which strikes said guard and passes over it, the spring f' yielding for this purpose, and falls down over that part of the guard which curves down behind said wheel, so as to hold the car from running away before the proper time. I prefer to construct the guards at their rear part in the form shown in Fig. 2, as this form will enable the latch to hold the car with a spring of less power than the form shown in the other views, which is desirable on account of the resistance which the spring offers to the raising of the latch over the guard. I prefer, also, to connect the guards to the car-frame on one side, as seen at e³, Figs. 3 and 7, to enable the wheels to be taken out and replaced with facility.

A projection, G, is attached to the upright A, and made adjustable vertically thereon by means of a set-screw, g. This projection is set at a sufficient height above the level of the point at which the hook B is secured to give the necessary pitch to the wire to cause the car to run down the incline to the cashier's desk.

The operation is as follows: Normally, the end at the sales-counter is below that at the cashier's desk, as shown in Fig. 1. The package and cash are placed in the basket at this

end. Then, by pulling on the belt D', the wire 40 at this end, with the basket, is raised to the position shown in Fig. 4. The projection G, coming in contact with the rear end of the latch, presses it down until the opposite end is raised sufficiently to release the car, and 45 the car then runs down the incline to the cashier's desk, where it is caught by the latch at this end. As soon as the car is thus caught, the end of the wire at the sales-counter is immediately lowered, so as to make it incline 50 downward in this direction. The cashier, after making change, loosens the latch, and the basket then returns down in the incline to the sales-counter.

Yielding buffers H are placed at the ends 55 of the frames C to prevent jarring and noise.

What I claim as my invention, and desire to secure by Letters Patent, is—

In a cash and package carrier, the combination, with the track-wire C, of links C', for 60 attaching said track-wire to its support, having springs c applied between the ends of said links and the ends of the track-wire for permitting the track-wire to yield longitudinally under increasing or decreasing tension, 65 the straight vertical track a at one end of said track-wire, a sliding piece, D, pivotally connected to the link C', which is adjacent to the track a and adapted to run on said track, and a taut belt, D', supported parallel to said track on a pulley at each end of the belt, said 70 sliding piece being connected in said belt as a part thereof, as and for the purpose specified.

JAMES FRANCIS BARTLETT.
